PAOLO ZAPPILE, OF NEW YORK, N. Y.

CORNICE-MOLD.

1,265,860.

Specification of Letters Patent.

Patented May 14, 1918.

Application filed March 9, 1917. Serial No. 153,675.

To all whom it may concern:

Be it known that I, PAOLO ZAPPILE, a subject of the King of Italy, residing at New York city, in the county of New York and State of New York, have invented new and useful Improvements in Cornice-Molds, of which the following is a specification.

This invention relates to masonry and concrete structures, and more especially to implements employed in finishing the plastering with a cornice in the angle between the wall and ceiling; and the object of the same is to produce a hand tool in the form of a running mold.

The invention consists in the details of construction applied to a mold of this character so that it will close any miter, whatever the configuration or design of the cornice, and so that it will finish either an inner or an outer angle thereof.

Details of construction are set forth in the following specification, and reference is made to the accompanying drawings wherein:

Figure 1 is a sectional view through one side wall and its cornice and the ceiling, an elevation of the cornice on the next side wall at right angles thereto, and an elevation of the tool in use.

Figs. 2 and 3 are views of the right and left tools viewed as they appear when looking from above, and with a hand in outline applied to the left tool.

Fig. 4 is a similar view of a slightly modified form of the right tool.

In the drawings I have used the letter W to designate a wall, and C is the ceiling meeting the same at the angle A. In this angle is often formed a cornice consisting of an upright leaf U against the wall and a horizontal leaf H beneath the ceiling, and the exposed faces of these leaves may have any suitable design or configuration. The present invention is a tool or implement known as a "running mold" by means of which the plasterer may give to the faces of both leaves of the cornice the desired configuration clear up into the angle at the corner of the room. It is to be understood that the cornice which is usually made of plaster of Paris or like plastic substance such as Kingstone or the like, is applied to the wall and to the ceiling rather roughly at first, and the outline of its original face is

indicated at X in Fig. 1; and it is the object 55 of this invention to provide a tool in the shape of a running mold by means of which the design configuration can be given to this cornice by shaping it or planing off the surplus material as it were.

Coming now to the details of construction and referring to the same by reference numerals, the frame of this tool which is preferably of wood or other light material comprises a slipper 1 which stands in a horizontal plane when the mold is being used, a blade 2 which stands in a vertical plane when the mold is in use and whose lower edge is attached to the upper face of the slipper by any suitable means, as by being set into a recess 3 therein and firmly secured in said recess, and a handle 4 above the slipper and behind the blade and firmly connected to both, and serving as a brace to hold them strictly at right angles to each other. Secured to the working face of the blade by suitable means such as screws or nails 5 a metal plate constituting the templet 6 whose working edge 7 projects beyond the corresponding edge of the blade 8 and is given a configuration which will impart the proper design to the upright and horizontal leaves of the cornice when their faces are finally reduced to their finished condition. I desire it understood that any 85 design of cornice may be made with this tool, whether the faces of its leaves are more or less elaborate than as shown in the drawings and whether they are wider or narrower. For this purpose it may be desirable to have the templet removably attached to the blade, so that the one illustrated herewith can be taken off and another supplied having a different configuration on its working edge 7; but more probably another pair of tools will be used in that case, so that the necessity for removing the templet will be obviated. As seen in Figs. 2 and 3 the tool is made in two members, the former being a right hand member 100 and the latter a left hand member, and when working into a right-angular corner the blade and templet of each member is set at strictly forty-five degrees to the outer edge 8 of the slipper which travels along the wall 105 below the cornice and against the face of the finished plaster. For the purpose of keeping the slipper always parallel with the

wall W , its edge 8 may be provided with a plurality of wear faces or shoes 9, or a single shoe may be attached thereto and continued throughout the full length of the edge 8. Correspondingly the upper edge of the blade 2 at its rear or heel end may carry a wear plate or shoe 10. When the latter travels in contact with the face of the plastering on the ceiling, while the shoes or shoe 10 on the outer edge 8 of the slipper travels in contact with the face of the plastering on the wall, the entire mold is held and maintained in proper position with respect to the cornice so that when it is advanced along the line indicated by the arrow, the proper design configuration is given to the upright and horizontal leaves of the cornice as shown.

In the use of this tool or mold, the cornice is of course at first in its unfinished condition as indicated by the line X . When the right hand tool shown in Figs. 1 and 2 is applied and moved to the left as indicated by the arrow in Fig. 1, the working edge 7 of its templet 6 cuts away or plows off the excess material from the line X down to the line of the face of the finished leaves of the cornice, and this excess material, being forward of the templet and the blade, drops from the tool onto the hawk (not shown) and which is usually carried in the other hand of the workman at the same time. Such would be the result with the tool shown in Fig. 4. I preferably extend the base plate or slipper, however, as seen in the remaining views, so as to form a small shelf 11 beyond the active face of the templet and below the line of the upright leaf U of the cornice, taking care to cut away the forward end of the shelf at 12 so that it shall not extend to the front end of the blade and templet at the point 13, and thereby leaving a space over which the surplus material may fall onto the hawk referred to. In the first passage of this tool along the line indicated by the arrow, much surplus material will be removed and doubtless it will accumulate upon the shelf 11 and run off the same onto the hawk; but in subsequent passages of the tool, after the surface of the cornice has been carefully moistened or wetted as usual when it is nearing completion, but little if any surplus will be shaved or planed off, as it were, and this will fall upon the shelf which meanwhile has been relieved of what formerly accumulated there. Thus the shelf is utilized as it were to catch the drippings, and the operator at this time may have his other hand free because there is no necessity of now carrying the hawk. The advantage of the shelf is now apparent, because invariably the tendency of the artisan at the last moment when his cornice is being finished is to use both hands to hold the tool closely up in the corner and perfect his job

while the plaster is yet in condition to be worked. Moreover, either he or his mate must work with the other tool along the adjacent wall and up into the same corner, and it would not be desirable to have the shelf extend completely to the point 13 because when the latter strikes the corner the shelf will not strike the plastering and certainly should not strike the upright leaf of the other cornice. Finally, the space left by shortening the shelf gives the artisan a chance to pass his fingers around the front end of the tool, and I may even cut away the corner of the shelf as indicated at 15 to give a place or rest for the thumb.

The use of the left hand tool shown in Fig. 3 is the same, excepting that of course it will form the cornice along the wall at the left side of Fig. 1 instead of that in the background thereof as indicated. Thus by the use of a pair of complementary or companion tools as shown in Figs. 2 and 3, no matter what the shape of the working edge 7 thereof, this invention may be applied to any mold that closes a miter at the corner as described. While I have shown the blade and templet standing across the slipper at strictly forty-five degrees, which will be their position when the walls at the corner of the room make a right angle, it will be clear that by setting these elements at different angles to the slipper miters of other angles might be closed in corners which are either obtuse or acute, but this need not be elaborated in the drawings or description. Yet I do not wish to be limited to the size or shape of parts, and have described wood as used only by preference because it is light.

What I claim as new is:—

1. The herein described running mold, the same comprising a slipper having across its upper face an oblique recess extending to its corner, shoes along the active edge of said slipper, an upright blade whose lower edge is secured in said recess and extends to the corner of the slipper and whose front and upper edges are cut out roughly to conform with the configuration of the cornice to be produced, the rear extremity of its upper edge being carried upward into a heel, a shoe thereon, a templet removably secured to the front face of said blade with its working edge projecting beyond the edge of the blade and its front end coincident with the corner of the slipper, the latter projecting beyond said templet to produce a shelf terminating short of the front end of the templet, and a handle connecting the blade and slipper.

2. The herein described running mold, the same comprising a slipper having across its upper face an upright blade extending to the corner of the slipper and whose front and upper edges are cut out roughly to conform with the configuration of the cornice to be

produced, the rear extremity of its upper edge being carried upward into a heel, a templet secured to the front face of said blade with its working edge projecting beyond the edge of the blade and its front end coincident with the corner of the slipper, the latter projecting beyond said templet to produce a shelf terminating short of the front

end of the templet, and a handle on the slipper. 10

In testimony whereof I affix my signature.

PAOLO ZAPPILE.
